Primary Examiner — George D. Kirschbaum

Assistant Examiner — Joseph J Kukella

(74) Attorney, Agent, or Firm — Thompson Hine LLP

(57) **CLAIM**

The ornamental design for tire tread, as shown and described.

DESCRIPTION

FIG. 1 is a front view of the design;

FIG. 2 is a detail view of a portion of FIG. 1;

FIG. 3 is a perspective view of the design of FIG. 1;

FIG. 4 is a side view of a first side of the design of FIG. 1; and,

FIG. 5 is a side view of a second side of the design of FIG. 1.

In the drawings, the broken lines depict environmental subject matter only and form no part of the claimed design.

1 Claim, 5 Drawing Sheets(56)
